UNITED STATES PATENT OFFICE.

ISAAC HUBBELL, OF PEORIA, ILLINOIS.

MINING-BIT.

1,312,732.

Specification of Letters Patent.

Patented Aug. 12, 1919.

Application filed November 26, 1917. Serial No. 204,011.

To all whom it may concern:

Be it known that I, ISAAC HUBBELL, a citizen of the United States, residing at Peoria, in the county of Peoria and State of Illinois, 5 have invented a new and useful Mining-Bit, of which the following is a specification.

This invention relates to bits for use in connection with augers such as used in coal mining, one of the objects of the invention being to provide bits which can be attached readily to an auger and which will cut quickly into the coal without choking, this being due to the fact that the bits are arranged off center, thus to cut around a 10 core which will chip off and permit the cuttings to pass readily from the hole produced by the bits.

Another object is to provide a bit so shaped as to be of the maximum strength, 20 and which can cut through the hardest substances in the mine without quickly dulling, this being due to the shape of the cutting edge and the temper.

With the foregoing and other objects in view which will appear as the description of the invention proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

In the accompanying drawings the preferred form of the invention has been shown.

In said drawings

Figure 1 is a side elevation of an auger having attached thereto bits such as constitute the present invention.

Fig. 2 is a perspective view of one of the bits.

Fig. 3 is a front elevation of a bit.

Fig. 4 is an end view of a bit.

Referring to the figures by characters of reference 1 designates an auger of the usual type but instead of being provided at one end with an integral bit, as ordinarily, it is flattened to form a tongue 2 tapered toward 50 its free end and provided along its center with spaced openings 3. This tongue is adapted to extend between opposed similar bits which have been shown in detail in Figs. 2, 3 and 4 and which are made of tem-

pered steel capable of withstanding the 55 wearing action of very hard substances.

As shown in the drawings each bit includes a flat attaching plate 4 having openings 5 for the reception of bolts or the like extending laterally from one side edge of the plate 4 is a flange 6 which gradually increases in width downwardly. The lower end of the flange merges into a cutting blade 7 which is curved transversely thus to present a concave advancing edge and the lower or active edge of the blade is curved in the direction of its length and terminates at its outer end in a point 8 which is in advance of the inner end of the cutting edge. The 65 flange 6 and the opposed edge of the plate 4 converge downwardly so that when the plate is attached to the tongue 2 said flange and the opposed edge of plate 4 will register with the corresponding edges of the tongue. 75

In practice two bits such as described are secured to opposed faces of the tongue 2, as shown. The auger can then be used as ordinarily and, as the cutting edges of the bits are located away from the axis of rotation 80 of the auger, it will be apparent that these bits will cut around a core which will thus chip away, allowing the bits to enter the coal freely without danger of choking. The advancing points 8 of the bits will cut into 85 the coal and be followed by the curved highly tempered cutting edges, the cuttings working outwardly along the curved surfaces of the flanges 6 and the blades of the bits producing a cut that is almost semi- 90 spherical. Should one of the bits become worn or broken it could be removed readily and another substituted, it being unnecessary to carry the entire heavy auger to the surface for this purpose. 95

What is claimed is:—

1. An auger having opposed bits at one end of the auger, each including an outwardly extending flange merging at one end into a cutting blade, said blade being curved 100 transversely and extending across one side of, but spaced from the axis of rotation of the auger, the blade having a cutting edge curved from end to end and terminating at its outer end in a point movable in advance 105 of its inner end.

2. An auger having opposed bits at one end of the auger, each including an out-

- wardly extending flange merging at one end into a cutting blade, said blade being curved transversely and having a cutting edge curved from end to end and terminating at 5 its outer end in a point movable in advance of its inner end, the two bits being oppositely disposed and having their blades crossed at opposite sides of the axis of rotation of the auger.
- 10 3. An auger having a tongue at one end, of similar bits secured to opposed faces respectively of the tongue, each bit including an attaching plate, and a flange extending outwardly from one side edge of the plate 15 and merging at one end in a transversely curved cutting blade, said blade having a cutting edge curved from end to end and terminating at its inner end in a point and at its outer end in another point movable in

advance of its inner end, the two bits having 20 their blades crossed at opposite sides of the axis of rotation of the auger.

4. An auger having broad bits at one end, said bits being oppositely disposed and crossed, each of the bits being bowed transversely to present a concave advancing surface, the cutting edge being curved from one side to the other of the bit and terminating in inner and outer points, the outer points being in advance of the inner points. 25 30

In testimony that I claim the foregoing as my own, I have hereto affixed my signature in the presence of two witnesses.

ISAAC HUBBELL.
